(57) **CLAIM**

The ornamental design for a cultivating tool, as shown and described.

DESCRIPTION

FIG. 1 is a perspective view of the cultivating tool according to the present invention;

FIG. 2 is a top plan view thereof;

FIG. 3 is an elevational view of the front of the cultivating tool according to the present invention, the back being substantially identical thereto;

FIG. 4 is a bottom plan view of the cultivating tool according to the present invention;

FIG. 5 is an elevational view of one side thereof; and,

FIG. 6 is an elevational view of the opposite side of the cultivating tool according to the present invention.
